UNITED STATES PATENT OFFICE.

WILLIAM J. BURTON, OF DETROIT, MICHIGAN.

METALLIC WINDOW.

No. 835,598.

Specification of Letters Patent.

Patented Nov. 13, 1906.

Application filed March 5, 1904. Serial No. 198,722.

To all whom it may concern:

Be it known that I, WILLIAM J. BURTON, a citizen of the United States of America, residing at Detroit, in the county of Wayne 5 and State of Michigan, have invented certain new and useful Improvements in Metallic Windows, of which the following is a specification, reference being had therein to the accompanying drawings.

This invention relates more specifically to an improvement in a sheet-metal frame and sash; and it consists in the particulars more fully hereinafter described, and pointed out in the claims, reference being had to the accompanying drawings, in which—

Figure 1 is a perspective view of a window-frame and pivoted self-closing sash embodying my invention. Fig. 2 is a vertical cross-section of Fig. 1. Fig. 3 is a horizontal section through the pivotal connection of the stile of the window-frame and side rail of sash on line $x-x$ in Fig. 2. Fig. 4 is a vertical section on line $y-y$, Fig. 3, with the parts separated. Fig. 5 is a central longitudinal section through the fixture in the sash-cord. Fig. 6 is an enlarged cross-section through the top rail of the sash.

The window-frame is composed of a sill A, stile B, and a head-jamb C, each composed of 30 sheet-metal plates bent into box-like form and connected together at the corners into a rigid frame.

The sill is integrally formed with an upwardly-projecting portion a , forming a stop 35 for the inner face of the bottom rail of the pivoted sash, and the head-jamb is formed with a downwardly-projecting portion c , forming a stop for the outer face of the top rail of the pivoted sash.

Each stile of the frame is formed by doubling the metal upon itself with two inwardly-projecting vertical ribs d , and within the folds of the ribs thus formed are secured two metal strips e , the outwardly-projecting 45 portions of which form vertical stops for the window-sash, one below and the other above the pivotal point. The free ends of these strips are bent over to form inclined ledges e' for the sash in its open position, as shown in 50 Fig. 2.

D is the sash, composed of top, bottom, and side rails formed of sheet metal bent into the desired shape and secured together into a rigid frame containing a panel E, of wire-glass or other fire-resisting material.

The bottom rail f and the side rails h of the

sash are formed with a glass-receiving channel i , while the top rail k is formed with a through-slot j , communicating with the glass-receiving channel i and adapted to form 60 a passage for the direct introduction of the wire-glass panel into the sash. The metal of the rail is turned inwardly to form the sides of said slot j , extending inward some distance and then folded inward and upward upon 65 itself to form narrow channels j' at each side of the inner end of the slot. The slot is closed by means of a cap l , removably secured in the slot and having a central downwardly-projecting rib adapted to bear upon 70 the upper edge of the glass panel, said rib being formed by folding the sheet of metal from which the cap is formed longitudinally upon itself, and yielding side portions at each side of the rib to engage the sides of the slot are 75 formed by bending the edges of the metal outward or laterally each way from the rib, thence downward, the downwardly-extending edges l' being adapted to enter the said narrow channels j' . The engagement of the 80 downwardly-extending edges l' with the channels j' prevents water from getting into the interior of the sash, and by providing the cap with yielding sides it may be pressed into the slot and will then be held in place. 85

The bottom rail of the sash is formed on the outside with a depending flange m , adapted to project down over an offset n formed on the sill, thereby forming a weather-strip, and the top rail is formed upon the inside in 90 like manner with a flange o , which projects upwardly. The sash is supported in the window-frame upon horizontal pivots, which are constructed as follows:

A pivot-hole p is tapped in each vertical 95 edge portion of the sash-body, and to the reverse side of the edge portion is riveted or otherwise permanently secured a reinforcing-plate q , provided with an apertured boss v .

Directly opposite the pivot-holes p in the 100 sash corresponding holes s are tapped in the stiles and through suitable reinforcing-plates t , which are permanently secured to the reverse face of the stiles. Through these holes a pivot-pin u projects outwardly into the 105 pivot-holes of the sash and pivotally supports the sash. Each pivot-pin is integrally formed with a plate r , which is secured by means of screws w to the window-stile. The heads of the screws are recessed into the stile 110 and have a screw-threaded engagement with the plate r only, whereby in turning the

screws with the screw-driver in one direction they will draw the plate *r* against the plate *t* and hold the pivot-pin in the projected position, (shown in Fig. 4,) while, on the other hand, they will cause the pivot-pin to recede into the stile if turned in the opposite direction. To prevent the screws from wholly unscrewing from the plate *r*, the free ends are upset.

- 10 It will be seen from Fig. 2 that if the sash is in the open position the heads of the screws *w* are perfectly accessible, and while the sash is in this position it can therefore be readily disengaged from the pivots and taken out for the purpose of glazing or for any other purpose and as readily be put into place again. When the sash is closed, the screws *w* are covered by the sash and cannot be operated. In connection therewith it will be noticed that 15 the open position of the sash is perfectly defined by the edges *e*², which form between them a guideway for the sash in taking it out or putting it back again. The sash is overbalanced on its pivot, so that it is self-closing 20 and locks itself closed by means of a spring-latch *G*, secured to the top rail of the sash and adapted to engage with a keeper *H*, secured to the head-jamb. The sash is adapted to be drawn open and held in its open position 25 by means of a chain or wire cord *I*, secured to the latch on the top rail of the sash and adapted to be engaged with a hook at its lower end, and in order to close the sash automatically in case of fire the cord or chain is made in two 30 sections, connected together by a fixture *J*, composed of two thimble-like halves, joined together at the meeting edges by fusible solder and forming the housing for a coil-spring *K*, inclosed therein under compression. The 35 two meeting edges of the fixture form between them an annular channel of V-shaped cross-section which receives the fusible solder, and thereby exposes it to the direct action of the heat in the room. Since the inclosed 40 spring is under considerable compression, it will be understood that the halves will be parted as soon as the heat softens the solder, and the device is therefore far more sensitive 45 to heat and quicker to act than if it depended 50 upon the solder alone.

What I claim as my invention is—

1. In a metallic window frame and sash each consisting of side, top and bottom members of sheet metal, said side members being provided with aligned pivot-openings in their adjacent walls, of plates within the side members of the frame having screw-threaded openings near each end and extending a distance vertically above and below the pivot-

openings, pivot-pins integrally formed with 60 said plates and adapted to project through the openings in the walls of the frame into the pivot-openings in the walls of the sash, and screws extending through the said walls of the frame vertically above and below the 65 pivot-openings therein and engaging the screw-threaded openings in the plates to rigidly secure the plates to the walls, and to project said pins through the pivot-openings.

2. In a metallic window frame and sash, 70 the combination of side, top and bottom members of sheet metal forming said frame and sash said side members being provided with aligned pivot-openings in their adjacent walls and said frame members being provided with countersunk openings vertically above and below the pivot-openings therein, reinforcing-plates permanently secured to the inner surfaces of the said walls of the window frame and sash and having holes opposite the 75 pivot-openings in said walls, and horizontal pivots for said sash each consisting of an elongated plate provided with an integral pivot-pin adapted to project through the pivot-openings in the frame into the pivot-openings 80 in the sash, said plate being of a length greater than the thickness of the sash and provided with screw-threaded openings near each end opposite the countersunk openings 85 in the said walls of the frame, and screws engaging said countersinks and the screw-threaded openings in the plate, said screws being of a length to permit the retraction of the pivot-pin within the frame and having 90 upset ends to prevent the disengagement of the screws from the plate and the withdrawal of the pin from the reinforcing-plate.

3. In a sheet-metal sash-frame, the combination of side rails and a bottom rail formed substantially rectangular in cross-section 100 with a glass-receiving channel in their inner wall; a top rail formed with a slot extending vertically through the same and with channels at each side of said slot near the bottom thereof; and a cap to close said slot provided 105 with a longitudinal rib to engage the edge of the glass formed by folding the sheet metal of the cap upon itself and provided with yielding edges to engage the sides of the slot and downwardly-extending flanges to engage the 110 channels in the slot, formed by bending the edges of the metal laterally and downwardly.

In testimony whereof I affix my signature in presence of two witnesses.

WILLIAM J. BURTON.
